CLAIM

The ornamental design for a baseball bat-shaped drinking vessel with home plate-shaped stand, as shown and described.

DESCRIPTION

FIG. 1 is a front perspective view of a baseball bat-shaped drinking vessel with home plate-shaped stand showing our new design;

FIG. 2 is a front view thereof;

FIG. 3 is a rear view thereof;

FIG. 4 is a left side view thereof; and,

FIG. 5 is a right side view thereof.

The broken line immediately adjacent to the shaded area defines the bounds of the claimed design and forms no part thereof. The broken lines depicting the remainder of the drinking vessel form no part of the claimed design.
